UNITED STATES PATENT OFFICE.

ANTHONY B. VAN RIPER, OF PATERSON, NEW JERSEY.

DESIGN FOR A BANNER.

43,170.

Specification for Design.

Patented Oct. 15, 1912.

Application filed August 9, 1912. Serial No. 714,318. Term of patent 3½ years.

To all whom it may concern:

Be it known that I, ANTHONY B. VAN RIPER, a citizen of the United States, residing at Paterson, in the county of Passaic and State of New Jersey, have invented a new, original, and ornamental Design for Banners, of which the following is a specification, reference being had to the accompanying drawing, forming part thereof.

The figure is a face view of the banner, showing my new design.

I claim:

The ornamental design for a banner, as shown.

ANTHONY B. VAN RIPER.

Witnesses:

LAURENCE J. GALLAGHER,

PHILIP D. ROLLHAUS.
